PLANT PROTECTOR

Hans Griesbacher, Taunton, Mass.

Application August 1, 1938, Serial No. 222,529

1 Claim. (Cl. 47—23)

This invention relates to plant and shrub protectors and an object of the invention is to provide a device of this character which while effective for protecting plants and shrubs will not injure dogs, and is not likely to be the cause of tearing clothes.

An object of the invention is to provide a device of this character characterized by simplicity of construction, inexpensive manufacture, and efficiency for the purpose designed.

The invention together with its objects and advantages will be best understood from a study of the following description taken in connection with the accompanying drawings wherein:

15 Figure 1 is an elevational view illustrating the application of the invention.

Figure 2 is an elevational view of the protector.

Figure 3 is a fragmentary side elevational view of the protector.

20 Figure 4 is a sectional view taken substantially on the line 4—4 of Figure 2.

Figure 5 is an elevational view showing the anchor plate from one side of the latter, and

25 Figure 6 is an elevational view of the blank from which the anchor plate is formed.

Referring to the drawings by reference numerals it will be seen that the protector comprises an anchor plate 5 and a wire 6.

The plate 5 is formed from a single blank of 30 metal or other suitable material cut, shaped and dimensioned to provide a substantially rectangular body sharpened to a point 7 at one end and pressed out to provide longitudinal strengthening or reinforcing ribs 8.

35 Adjacent the upper end thereof the plate 5 has spring clips 9 struck out therefrom while at about the center of the plate there is struck out therefrom a spring clip 10.

The wire 6 is of any suitable length and in

actual practice is bent into a substantial U, and adjacent the closed end of the U is disposed at one side of the plate 5 with the wire at the bight 9 of the U engaged with the clip 10 and the legs of the U engaged with the clips 9 as 5 clearly shown whereby to detachably secure the wire to the plate so as to extend upwardly from the plate.

When set up for use the legs of the wire 6 are curved to diverge as they approach the open end 10 of the U and are also curved longitudinally out of the plane of the plate 5 and consequently away from the plant or shrub 11 as clearly shown in Figure 1.

Obviously any desired number of protectors 15 may be used the protectors being arranged either in the form of a circle, or semi-circle about the plant 11 as suggested in Figure 1, with the anchor plate 5 embedded in the ground and the wire 6 extending upwardly and curved away from the plant so as not to interfere with the plant and yet at the same time protect the plant from dogs.

It is thought that a clear understanding of the construction, utility and advantages of a protector embodying the features of the present invention will be had without a more detailed description.

Having thus described the invention what is claimed as new is:

A protector of the character described comprising an anchoring plate provided on one side thereof with spring clips and a wire bent into the form of a U and having the bight portion of the U engaging one of the clips and the leg portions of the U engaging other of the clips in a manner detachably securing the wire to the anchor plate 30 at the closed end of the U.

HANS GRIESBACHER.
